OPERATING MEANS FOR PRESS CONTROL
MECHANISMAngus F. Hanney, Norwood, Ohio, assignor to The
American Laundry Machinery Company, Nor-
wood, Ohio, a corporation of Ohio

Application October 1, 1935, Serial No. 43,067

7 Claims. (Cl. 38—25)

This invention relates to a control mechanism for a pressing machine.

I have provided herein an improved control mechanism for a pressing machine having a pair of coacting pressing members and motor means for closing the members first in a preliminary step where the operator's hands are safe from injury and, second, in a final step which places the pressing members under heavy pressure. The control mechanism is provided with two members for controlling the first step, these members being so spaced as to require the simultaneous use of both hands of the operator. The control member for the second step is arranged to be automatically operated upon movement of one of the first named control members when released. My improved control mechanism as applied to the type of press just described includes a control member for the first step of the press closing movement, means biasing this member in its "off" position and means for actuating the control member for the second step of the press closing operation actuated by this biasing means.

My invention also includes a novel latching mechanism between two control members, each for a different motor, so that operation of the control member for one motor latches the same with the control member for the other motor, whereupon return movement of the first control member actuates the second control member.

Other advantages and novel features of my pressing machine control will be obvious as the description proceeds and the essential features will be summarized in the claims.

In the drawing, Fig. 1 is an end elevation partly in section of a pressing machine embodying my invention and with the control mechanism shown diagrammatically; while Figs. 2 and 3 are partial views showing the control mechanism of Fig. 1 in various of its operated positions.

While my control mechanism is applicable to various types of presses, I have chosen to illustrate the same as applied to a machine such as is used in pressing laundry articles and garments.

I have also shown the control mechanism applied to a pressing machine in which each pressing member is movable toward the other to completely close the press but the principles here disclosed might also be applied to a machine in which one member was moved by two steps, first into a preliminary closed position and second into a final closed position. In the form shown, on a frame 10 is pivotally mounted a head lever 11 which carries a pressing head 12. The pressing head is biased in open position by a spring

13 and is moved to closed position by a pair of toggle links 14 and 15 connected between the rear end of the head lever and the frame and actuated by a motor 16. This motor has a cylinder 16a housing a piston 16b whose rod 16c is connected to the toggle links. A small vent 16d is provided in the forward end of the cylinder for a purpose later disclosed. Motive fluid is supplied to motor 16 from a supply conduit 17 through valves in spaced casings 18 and 19 connected together by a conduit 20 and connected with motor 16 by a conduit 21. Valve casing 18 houses a normally closed inlet valve 18a which is biased by a spring 18b toward closed position. The valve is actuated by a manual 22, details of which will be later described. Valve casing 19 houses a normally closed inlet valve and a normally open outlet valve and is actuated by a manual 23. Manuals 22 and 23 are spaced apart before the operator at the front of the press in a manner to require a hand on each of them to actuate the valves in casing 18 and 19 and both of these valves must be operated to actuate motor 16 because if manual 22 is released valve 18a closes and motor 16 will be vented through 16d. Whereas if manual 23 is released the exhaust valve in casing 19 will be opened and the inlet valve closed and the motor 16 will be evacuated.

For coaction with the pressing head a pressing bed 24 is mounted in the frame 10 for a limited vertical movement relative thereto and guided in such movement by pins 24a which enter suitable bores in the frame. The bed is lifted by a cylinder and piston motor 25 having a cylinder 25a which houses a piston 25b whose stem 25c is adapted to raise the bed. Motive fluid is supplied to motor 25 through conduit 26, valve casing 27 and conduit 28. Valve casing 27 houses a normally closed inlet valve 27a and a normally open outlet valve 27b biased to their normal position by a spring 27c. Both valves are mounted on a common stem 27d which is operable by a member 29 and more particularly by an upstanding arm 29a rigid therewith. Manual 22 and member 29 are mounted to move freely on a common pivot 30. Pivoted on the manual 22 is a latching member 31 which is in the form of a bellcrank having a forwardly extending arm 31a and a downwardly extending arm 31b. The downwardly extending arm has a notch 31c which is adapted to engage a pin 29b on member 29 when the notch and pin register. The bellcrank member 31 is biased in a counterclockwise direc-

tion by a spring 32 which is secured to a stud 22b rigidly connected with the manual 22.

With the parts in the position of Fig. 1, the operator arranges the lay of the work upon the bed 24 and depresses manuals 22 and 23 as shown in Fig. 2. This actuates the valves in casings 18 and 19 thus admitting pressure fluid to motor 16 which makes a power stroke moving the toggles into and beyond straightened position and moving the head 12 to a position adjacent the bed. At the same time spring 18b is compressed and notch 31c engages pin 29b. To completely close the press the operator then releases either manual 22 or both manuals as shown in Fig. 3. Upon release of manual 22 both manuals 22 and 23 move as a unit in counterclockwise direction about pivot 30 impelled by spring 18b which is of sufficient strength to overcome spring 27c and to cause this movement of both manuals. The arm 29a engages stem 27d closing valve 28b and opening valve 27a and thus admitting pressure fluid through conduit 28 to motor 25 which makes a stroke vertically upward and raises the bed into pressure engagement with the head. This holds the pressing members in engagement because the toggle links 14 and 15 are in a strut forming position between the rear end of the head lever and the frame. The release of manuals 22 and 23 or either of them is sufficient to evacuate motor 16. The press remains closed until the operator depresses the arm 31a of bellcrank 31 thus disengaging notch 31c from pin 29b, which permits member 23 to rotate in a clockwise direction about pivot 31 and spring 27c returns the valves in casing 27 to normal position to evacuate motor 25. Thereupon the bed and piston 25b move downwardly due to the weight of the parts and spring 13 returns the pressing head to open position aided by a snubber and kick mechanism 33.

What I claim is:

1. In a pressing machine a pair of coacting relatively movable pressing members, motor means operable in two steps for causing relative approach movement between said pressing members, a first step into preliminary position and a second step into final pressing position, control means for said motor means including a member for controlling each of said steps, and an operative connection between a control member for the first step and a control member for the second step operative to move said second step control member in fluid supply direction upon movement of said first step control member in fluid cut-off direction.

2. In a pressing machine a pair of coacting relatively movable pressing members, motor means operable in two steps for causing relative approach movement between said pressing members, a first step into preliminary position and a second step into final pressing position, control members for said motor means for controlling each of said steps, a control member for controlling the first step operation of said motor means and biased toward fluid cut-off position, and a latch connection between said control member and the control member for said second step operation, said latch member being adapted to be engaged by movement of said first step control member to fluid supply position.

3. In a pressing machine a pair of coacting relatively movable pressing members, a motor for causing relative movement between said members and into a preliminary position, a second motor for causing relative movement between said members and into final pressing position, a control member for said second motor associated with one of said control members for said first motor, and a connection between said control members for moving said second motor in fluid supply direction.

member for each motor, and a connection between said control members operable to move said second motor control member in fluid supply direction by movement of said first motor control member in fluid cut-off direction.

4. In a pressing machine a pair of coacting relatively movable pressing members, a motor for causing relative movement between said members and into a preliminary position, a second motor for causing relative movement between said members and into final pressing position, two spaced safety control members for said first motor both of which must be operated to actuate the motor, a control for said second motor associated with one of said control members for said first motor, and a connection between said associated control members for actuating the control member for said second motor in fluid supply direction upon movement of the control member for said first motor in fluid cut-off direction.

5. In a pressing machine a pair of coacting relatively movable pressing members, a motor for causing relative movement between said members and into a preliminary position, a second motor for causing relative movement between said members and into final pressing position, two spaced safety control members for said first motor both of which must be operated to actuate the motor, a control for said second motor associated with one of said control members for said first motor, a latch carried by one of said control members and automatically engaging a portion of the other of said associated control members upon movement of the first motor control member in fluid supply direction and operable to move said second motor control member in fluid supply direction by movement of said first motor control member in fluid cut-off direction.

6. In a pressing machine a pair of coacting pressing members, mechanism for moving one of said members into position adjacent the other, said mechanism being constructed and arranged so that said one member when in said position resists pressure against it, a motor for moving said mechanism to place said one member in said position, a control member therefor, fluid actuated means for moving the pressing surface of said other member against said one member in said adjacent position, a control member for said last named means, and a connection between said control members for moving said second named member in fluid supply direction by movement of said first named member in fluid cut-off direction.

7. In a pressing machine a pair of coacting pressing members mechanism for moving one of said members into position adjacent the other, said mechanism being constructed and arranged so that said one member when in said position resists pressure against it, a motor for moving said mechanism to place said one member in said position, a control member therefor, fluid actuated means for moving the pressing surface of said other member against said one member in said adjacent position, a control member for said last named means, means biasing said first named control member in fluid cut-off direction, means for automatically coupling together both of said control members upon movement of said first named control member in fluid supply direction, and said control members being arranged to move said second named control member in fluid supply direction by movement of said first named control member in fluid cut-off direction.
